TRANSPARENT FILTERING AND LIQUID-TREATING UNIT

Herbert J. Atkinson, Sudbury, Mass.

Application May 27, 1953, Serial No. 25,197

Term of patent 7 years

(Cl. D16—2)

To all whom it may concern:

Be it known that I, Herbert J. Atkinson, a citizen of the United States, residing at Sudbury, in the county of Middlesex and State of Massachusetts, have invented a new, original, and ornamental Design for a Transparent Filtering and Liquid-Treating Unit, of which the following is a specification, reference being had to the accompanying drawing, forming part thereof.

Fig. 1 is a perspective view of a transparent filtering and liquid-treating unit, showing my new design;

Fig. 2 is a plan view thereof;

Fig. 3 is a fragmentary longitudinal sectional view taken on line 3—3 of Fig. 2.

I claim:

The ornamental design for a transparent filtering and liquid-treating unit.
